UNITED STATES PATENT OFFICE

2,399,800

METHOD OF MAKING SHOVELS

Richard Harte, Parkersburg, W. Va., assignor to
 Ames Baldwin Wyoming Co., Parkersburg,
 W. Va., a corporation of Delaware

Application January 14, 1944, Serial No. 518,299

3 Claims. (Cl. 76—113)

This invention relates to shovels and the object is to provide a shovel of strong and simple construction which may be made inexpensively and with but little labor from simply produced parts. While not limited thereto, the invention finds a particularly advantageous application to the type of shovel known as a scoop which has a deep, bowl-like blade.

My invention will be well understood by reference to the following description taken in connection with the accompanying drawing wherein I have shown by way of example a particular form of shovel illustrative of its invention and the steps of its manufacture. In this drawing:

Fig. 1 is a longitudinal section of a tubular blank;

Fig. 2 is a cross-section on the line 2—2 of Fig. 1;

Fig. 3 is a view showing the portion of the shovel as made from the blank of Fig. 1 in an intermediate stage;

Fig. 4 shows a further step in the development;

Fig. 5 is a plan view on a reduced scale showing the blade proper or bowl of the shovel;

Figs. 6 and 7 are a plan and longitudinal section respectively of the finished shovel with the handle broken away; and

Fig. 8 is a section on the line 8—8 of Fig. 6 on a larger scale.

The shovel shown as an example of the invention comprises the blade proper and what may be characterized as a tubular back-bone which intersects the base or bottom of the blade and the rear flange, if one is present, and gives stiffness and an intermediate portion which serves to give the proper lift to the shovel and an outer portion providing a handle-receiving socket.

I believe the construction of the shovel will be most clearly understood if I describe in detail the preferred method of forming the same.

In Figs. 1 and 2 I illustrate a length of cylindrical tubing B having a continuous circumferential wall. Conveniently by means of the process known as cold swaging whereby the tube is subjected to a large number of successive blows, the tube is brought into the form B₁ shown in Fig. 3 in which it is seen to have its forward end tapering in diameter while the wall of that end is correspondingly increased in thickness and so strengthened. The forward edge is shown closed in Fig. 3 and this may be effected by the swaging operation or separately.

The modified tube B₁ is then bent to goose-neck form, as shown in Fig. 4, to provide, enumerating from the open rear end, that at the right-

hand in the figure, a forwardly extending handle-receiving portion 10, an intermediate angular portion 12 and a forwardly extending distal portion 14. The portions 10 and 14 are at such an angle as it is desired to have between the plane of the blade bottom and the handle and the angular portion provides the desired lift.

Referring to Fig. 5, the blade body is formed from sheet steel and may have the bottom 16 and, in the case of a scoop as shown, a flange 18 about the two sides and rear of the bottom. A notch 20 is cut in the rear of the blade body through the flange and into the bottom for a suitable distance. This notching, as it breaks the continuity of the outer portion of the metal blank which is bent up to form the flange 18, permits a deep bowl to be formed.

The width of the notch 20 is such that the portion 14 and part of the portion 12 of the tubular back-bone element shown separately in Fig. 4 will fit therein in such manner that a line drawn between the margins of the notch will extend secantwise across the cross-section of the tube. Desirably the margins of the notch engage the wall of the tube along a chord at the under side of the diameter since the projection of the back bone at the bottom of the blade should not be great. This arrangement also insures a firm contact of the wall of the tube with the margins of the notch since the former may be pressed home in the latter.

When the parts have been so assembled the margins of the notch are united to the side wall of the tube, the bottom 16 to the portion 14, and the flange 18 to the portion 12, by fusion welding. This welding is preferably arc welding involving the deposit of extraneous metal w (see Fig. 8) forming fillets at the angles where the blade body joins the tube at either side of the latter.

The resultant shovel is very light and strong. A socket with unbroken circumferential wall to receive the handle is provided. The blade is strongly reinforced by the tubular back bone provided by the portion 14 of the seamless tube and the flange 18, when present, is also strongly supported. The construction is light, comparing favorably with the so-called hollow-back shovel, but there is no hollow in the back to catch or retain dirt. A deep scoop body may be made easily when desired because of the notched construction, as illustrated in Fig. 5. Obviously the method of manufacture as described is easy and inexpensive.

I am aware that the invention may be em-

bodied in other specific forms without departing from the spirit or essential attributes thereof, and I therefore desire the present embodiment to be considered in all respects as illustrative and not restrictive, as is in fact clear in several matters from the description itself. Reference is to be had to the appended claims to indicate those principles of the invention exemplified by the particular embodiment described and which I desire to secure by Letters Patent.

I claim:

1. A method of making a shovel or like tool which comprises bending a tube having a continuous circumferential wall and a closed end into goose-neck shape, cutting a notch through the back of a blade, fitting the end portion of the tube into said notch and welding the margins of the notch to the sides of the tube by fusion of extraneous metal therewith.

2. The method of making a shovel or like tool 20

which comprises swaging a tube which has a continuous circumferential wall to reduce the outer diameter and thicken the wall thereof toward one of its ends, cutting a notch through the back of a blade, fitting said end portion of the tube into said notch and welding the margins of the notch to the sides of the tube by fusion of extraneous metal therewith.

3. The method of making a shovel or like tool 10 which comprises swaging a tube which has a continuous circumferential wall to reduce the outer diameter and thicken the wall thereof toward one end, and incorporating said end as the rear central portion of the blade proper with the 15 other end of the tube projecting as a handle-receiving socket by presenting the palm-forming portion of the blade to the exterior wall of said end and securing it by welding.

RICHARD HARTE.
